END SUPPORT FOR A GARMENT DISPLAY RACK

Maurice Cohen, 3580 NW. 52nd St.,
Miami, Fla. 33142

Filed Aug. 7, 1972, Ser. No. 278,592

Term of patent 14 years

Int. Cl. D6—06

U.S. Cl. D6—193

FIG. 1

FIG. 2

FIG. 3

FIG. 4

FIG. 5

FIG. 1 is a perspective view of an end support for a garment display rack showing my new design;

FIG. 2 is a front elevational view thereof;

FIG. 3 is a side elevational view thereof;

FIG. 4 is a top plan view thereof; and

FIG. 5 is a bottom plan view thereof.

I claim:

The ornamental design for an end support for a garment display rack, substantially as shown.
